CLOSURE MEANS FOR FURNACE VESTIBULE
Henry W. Schramm and Alfred G. Parkes, Toledo, Ohio,
assignors to Midland-Ross Corporation, Toledo, Ohio,
a corporation of Ohio

Filed Feb. 3, 1964, Ser. No. 341,988
5 Claims. (Cl. 110—173)

This invention relates to improved closure means for a furnace vestibule and particularly for vestibule of a furnace adapted to contain a combustible metallurgical treating atmosphere.

In the heat treating of metal work pieces in a combustible treating atmosphere, as in the carburizing of ferrous metal work pieces in a carbonaceous atmosphere, it is customary to provide the inlet to the treating furnace with an antechamber, usually called a vestibule. Work pieces to be treated in the furnace are initially charged into the vestibule which initially is sealed from the furnace by means of a door. After the work pieces are inside the vestibule, and prior to the time when they are transferred into the furnace treating chamber, the entrance to the vestibule is closed by closing means, such as a door. Then the vestibule is purged by continually adding fresh treating atmosphere thereto, as is commonly accomplished by permitting a controlled leakage of atmosphere from the furnace treating chamber to the vestibule, while simultaneously venting atmosphere from an effluent of the vestibule. The purpose of the purging step is to rid the vestibule of the air which will unavoidably pass thereinto when the door to the vestibule inlet is open to permit the entry of workpieces, so that air does not subsequently enter the furnace treating chamber.

The closure means heretofore frequently provided for closing the inlet to the vestibule when it is not desired to pass work pieces therethrough comprises a stationary substantially flat annular plate attached to the vestibule casing and circumscribing the vestibule inlet, and a substantially flat door plate of sufficient extent to cover the opening of the annular plate and movable into and out of abutting relationship with the annular plate. In such an arrangement the inlet to the vestibule is nominally sealed by the continuous annular plane of contact between the stationary substantially flat annular plate and a substantially flat annular portion of the door plate when the door is in abutting relationship to the annular frame.

Closure means according to the above have not always proven satisfactory, however. In a number of instances, it was known that the continuous seal between the annular plate and the abutting annular portion of the door plate was broken due to warpage or bending out of flatness of the annular plate and/or the door plate. Since a surface vestibule is normally maintained at a slight positive pressure to prevent the influx of air, a break in the continuity of the seal at the inlet to the vestibule will permit atmosphere gases from the vestibule, which frequently contain carbon monoxide, to escape into the air.

Accordingly, it is the object of this invention to provide closure means for a furnace vestibule opening which can limit to an acceptable level the escape of gases from the vestibule when the opening is closed, notwithstanding some warpage or bending of various elements of the closure means.

For a further understanding of the invention, attention is directed to the following portion of the specification, the drawing, and the appended claims:

FIG. 1 is a fragmentary elevational sectional view of a furnace vestibule embodying closure means constructed in accordance with the present invention;

FIG. 2 is a front elevational view of the closure means taken on line 2—2 of FIG. 1, with portions thereof broken away to show various details of construction;

FIG. 3 is a plan view taken on line 3—3 of FIG. 1;
FIG. 4 is a fragmentary plan view showing a portion of the apparatus of FIG. 3 at an enlarged scale;

FIG. 5 is a sectional view taken on line 5—5 of FIG. 4;
FIG. 6 is a sectional view taken on line 6—6 of FIG. 5;

FIG. 7 is a fragmentary elevational sectional view of another embodiment of closure means constructed in accordance with the present invention;

FIG. 8 is a fragmentary front elevational view of the closure means of FIG. 7, taken on line 8—8 thereof; and
FIG. 9 is a fragmentary elevational sectional view of a modification of the embodiment of FIGS. 7 and 8.

Referring now to FIG. 1 of the drawing there is shown wall means 11 defining a vestibule 12 which serves as an antechamber to the treating chamber of a metallurgical heat treating furnace (not shown) in a customary manner. Vestibule 12 is provided with an opening 13 through which workpieces may be added from and/or removed to an exterior work support table 14. Work support means such as roller rails 15 are provided within vestibule 12 for supporting the workpieces therein. In the illustrated embodiment, work support table 14 is shown as comprising similar roller rails 16 aligned with roller rails 15 to permit workpiece carries (e.g. a furnace tray or basket) to be rolled into and/or from the vestibule without the need for a lifting device.

The vestibule illustrated in FIG. 1 is applicable to batch type furnaces of a popular style in which a workpiece quenching station 17 is disposed subjacent the vestibule in the manner described in U.S. Patents 2,940,619 and 2,898,101. However, it is contemplated that the invention possesses utility in connection with vestibules of other types of batch furnaces and in connection with the inlet and/or outlet vestibules of continuous type furnaces.

Opening 13 to vestibule is circumscribed by an annular member, shown generally at 18, which is attached to wall means 11. Annular member 18 comprises a plate 19 having a generally flat annular face 21. During periods when it is not desired to introduce or remove workpieces from vestibule 12, as the case may be, opening 13 is closed by lowering a vertically reciprocable door, shown as comprising a generally flat plate 22, into position in front of opening 13. Door 22 is of sufficient extent to have a generally flat annular surface portion 22a (FIGS. 4 and 5) adapted to abut against the face 21 of plate 19 when door 22 is lowered and to form a continuous annular seal therewith. The reciprocation of door 22 into and out the closed position is accomplished by means of a hoist mechanism 23 which may be manually or mechanically actuated. In its closed position door 22 is biased against plate 19 in customary fashion when wedges 24 carried by door 22 contact rollers 25 attached to wall means 11.

In the prior art it was common to attempt to seal a furnace vestibule by means of an annular seal such as that obtained between annular surface 22a of door 22 and annular face 21 of plate 19. Such prior installations were, however, plagued by serious disruptions in the continuity of the annular seal resulting from warpage or bending of one or the other of the constituent sealing members, viz. members corresponding to door 22 and plate 19. Previously, attempts have been made to eliminate or minimize the effect of these disruptions by carefully machining the abutting faces of the sealing members to a high degree of flatness and by stress relieving one or both of the sealing members. Also, it has been known to use unusual materials in the construction of the sealing members, such as the use of coreplate in the construction of the vestibule door. None of these expediencies, however, alone or in combination, has been effective to provide a vestibule closure seal of sufficient quality to maintain the rate of leakage of atmosphere gases from the ves-

tibule within acceptable limits in every case. Even in the case of designs that were heretofore relatively superior to such a number of the furnaces manufactured according to such a design would develop excessive rates of atmosphere leakage in service. These furnaces could not always be satisfactorily repaired, and when they were repaired, it was usually at considerable expense since it was usually necessary to send a field engineer from the manufacturer's office to the customer's plant to supervise the repair work.

According to this invention, however, it is possible to simply and rapidly correct serious disruptions in the continuity of the seal between annular face 21 of plate 19 and annular surface 22a of door 22. This is accomplished by providing a plurality of adjustment means disposed around one or the other of annular face 21 of the vestibule and annular surface portion 22a of the door for biasing localized portions of the one or the other face or surface portion out of its normal position (usually out of relatively true flatness) to close any localized gap which may develop between the abutting surface.

In the illustrated embodiment the adjustment means are carried by annular member 18 of the vestibule and comprise a plurality of biasing means 26 disposed at spaced loci in an annular pattern circumscribing opening 13 to vestibule 12. In a typical installation, the spacing between adjacent biasing means may be of the order of 4 to 5 inches. Each biasing means 26 comprises a stud 27 securely mounted in annular plate 19 and extending transversely therefrom toward the vestibule. Stud 27 slidably passes through the bore of an annular bolt 28 and a nut 29 is threaded on the external end of stud 27. Annular bolt 28 is threaded through a tapped aperture in an annular member 31 which is secured to wall means 11 of vestibule 12. The end of annular bolt 28 is slidably adapted to bear against the back of plate 19 (or against a member such as a washer 33 in contact therewith).

Annular plate 19 is maintained in a spaced relationship with respect to annular member 31 and the space therebetween, typically of the order of three-eighths inch, is packed with resilient sealing means, preferably moderately heat-resistant, such as spaced apart strands of asbestos rope 32, to prevent the escape of atmosphere gases from the vestibule therethrough.

Whenever a gap occurs between the frame and the door, the plate 19 is locally moved toward or away from the door to close the gap. In making this adjustment, both the annular bolt 28 and nut 29 holding stud 27 in position are moved. When a gap occurs by a "concave" bow along the engaging surface 22a of the door 22 or along frame engaging surface 21, nut 29 is loosened on stud 27 to permit the annular bolt 28 to be tightened to thereby force the frame engaging surface 21 toward door engaging surface 22a to close the gap. Nut 29 is only loosened enough to permit this adjustment and both washer 34 and washer 33 are in compression after adjustment. Adjacent means 26 would be moved in the opposite direction, i.e. nut 29 would be tightened drawing stud 27 and frame 19 up; annular bolt 28, of course, must be loosened to permit this adjustment.

FIGS. 7 and 8 illustrate an embodiment of the invention which is somewhat simpler in construction than that illustrated in FIGS. 1-6. According to this latter embodiment, an opening 113 to a vestibule 112 is circumscribed by an annular member 118 which is attached to the wall means 111 which serve to define vestibule 112. Annular member 118 comprises an annular plate 119 which may be non-adjustably assembled with the other constituent elements of member 118. Opening 113 may be closed by vertically reciprocable door 122 which may be operated in the manner of door 22 of FIG. 1. Door 122 is provided with an annular channel 141 which is adapted to be aligned with annular plate 119 and which is disposed with the channel opening facing toward annular plate 119.

The opening of channel 141 is filled with packing 142 of

moderate rigidity which extends toward plate 119 beyond the limits of channel 141 and which is backed up by a thin flexible metal plate 145. A braided groove packing available from Johns-Manville Company under their designation #JM-872 is suitable for packing 142. A seal 5 between door 122 and annular member 118 is, therefore, obtained when annular face 142a of packing 142 is biased against annular face 121 of member 119, as by means of wedges and rollers (not shown) in the manner of elements 24 and 25 of FIG. 1.

Any localized gap which develops as a result of a disruption in the continuity of contact between packing 142 and plate 119 may be corrected by adjusting those of a spaced plurality of biasing means 126 carried by door 122 in the region of the gap to bias a local portion of packing 142 toward plate 119 to eliminate the gap, or substantially reduce its size. Each of biasing means 126 comprises a set screw 143 threaded into a tapped hole 144 extending through door 122, including channel 141, in a direction generally transversely of the plane of contact between packing 142 and plate 119. Retraction of a localized portion of packing 141 from plate 119, as to accommodate a convex outward bow of plate 119, may be accomplished by adjusting those of biasing means 126 in the region of the bow away from packing 142 and thence by biasing packing 142 toward the adjusted biasing means, as by applying force against face 142a by hand or by biasing door 122 against plate 119.

In the embodiment of FIG. 9, which is similar to that of FIGS. 7 and 8, vertically reciprocable door plate 212 is provided with an annular L-shaped member 241 which defines a channel 241a with the outer edge 212a of door-plate 212. The opening of channel 241a faces toward the annular sealing surface 221 of annular member 219 which circumscribes the opening 213 of a vestibule. Channel 241a is provided with packing 242, similar to packing 142 of FIGS. 7 and 8, and similarly backed by a thin flexible metal plate 245. Packing 242 extends outwardly from channel 241a toward member 219 and abuts against surface 221 when doorplate 212 is in the closed position. A local portion of packing 242 may be biased toward surface 221 by one of a plurality of spaced biasing means 226 comprising a bolt 243 threaded through a hole in one leg of member 241, and extending generally transversely of doorplate 212 toward packing 242.

The best mode known to us to carry out this invention has been described above in terms sufficiently full, clear, concise, and exact as to enable any person skilled in the art to make and use the same. It is to be understood, however, that it is contemplated that other modes of practicing the invention can be made by a skilled artisan without departing from the scope of the invention which is defined only by the appended claims.

We claim:

55. 1. Apparatus comprising, in combination: wall means defining a vestibule having an opening; annular means connected to the wall means comprising an annular plate member having a first surface circumscribing the opening; movable door member having a second surface for abutting against the first surface for closing the opening; and a plurality of biasing means mounted on one of said members at spaced points disposed in an annular pattern circumscribing the opening for selectively biasing at least one local portion of one of said first and second surfaces 60 toward the other of said first and second surfaces for closing any localized gap therebetween when the first surface is in abutting relationship to the second surface, each of said biasing means being totally contained at one of said spaced points and operative to selectively bias a local portion independently of other of said spaced points.
65. 2. Apparatus according to claim 1 wherein the annular means comprises a second annular plate member attached to the wall means, and wherein the first annular plate member and second annular plate member are spaced apart from one another with the second annular plate

member being spaced on the opposite side of the first annular plate member from the first surface; and wherein the biasing means comprises means carried by the annular means for biasing the first annular plate member away from the second annular plate member toward the second surface thereby locally increasing the space between the first annular plate member and the second annular plate member.

3. Apparatus according to claim 2 wherein each of the biasing means comprises a port in the second annular plate member; a stud extending from the first annular plate member through the port; and a tightening nut on the end of the stud for biasing the first annular plate member toward the second annular plate member.

4. Apparatus according to claim 3 and further comprising a bolt threaded through second annular plate member and extending toward the first annular plate member for biasing the first annular plate member away from the second annular plate member.

5

5. Apparatus according to claim 4 wherein the bolt is threaded through the port in the second annular plate member and wherein the stud slidably passes through the aperture in the annular bolt.
